(57) **CLAIM**

The ornamental design for scalp treatment apparatus, as shown and described.

DESCRIPTION

1. Scalp treatment apparatus

Figure 1.1 is a perspective view of a scalp treatment apparatus;

Figure 1.2 is a front view thereof;

Figure 1.3 is a back view thereof;

Figure 1.4 is a left view thereof;

Figure 1.5 is a right view thereof;

Figure 1.6 is a top view thereof; and

Figure 1.7 is a bottom view thereof.

The broken lines shown in Figure 1.7 depict portions of the scalp treatment apparatus that form no part of the claimed design.

1 Claim, 7 Drawing Sheets
